FORK OR THE LIKE

Earl B. Pardon, Newburyport, Mass., assignor to Towle Manufacturing Company, Newburyport, Mass., a corporation of Massachusetts

Application October 11, 1955, Serial No. 38,325

Term of patent 14 years

(Cl. D54—12)

Fig. 1 is a front elevation of the fork, the front and back of the handle being identical;

Fig. 2 is a side view, both sides being identical of Fig. 1;

Fig. 3 is an end view of the tip of the handle showing a decorative inset therein;

Fig. 4 is a cross-section intermediate the tip and bolster; and

Fig. 5 is a cross-section at the bolster.

1 claim:

The ornamental design for a fork or the like, substantially as shown and described.
